UNITED STATES PATENT OFFICE.

WILLIAM S. WOLFE, OF AKRON, OHIO.

DESIGN FOR A TIRE-TREAD.

49,590.

Specification for Design.

Patented Aug. 29, 1916.

Application filed June 9, 1916. Serial No. 102,779. Term of patent 14 years.

To all whom it may concern:

Be it known that I, WILLIAM S. WOLFE, a citizen of the United States, residing at Akron, in the county of Summit and State of Ohio, have invented a new, original, and ornamental Design for a Tire-Tread, of which the following is a specification, reference being had to the accompanying drawing, forming part thereof.

The figure is a fragmentary perspective view of a tire tread showing my new design.

According to my design, the tread of the tire bears a centrally located continuous circumferential rib. On each side of the rib is a circumferential series of uniformly spaced transverse ribs which abut at their inner ends against the central circumferential rib and terminate at their outer ends short of the side walls of the tire.

I claim:

The ornamental design for a tire tread as shown and described.

WM. S. WOLFE.
